Patented Sept. 23, 1958

183,587

COMBINED TRAY, BRUSH, AND UTENSIL HOLDER

Wilfred Sheppard, West Orange, N. J.

Application March 6, 1958, Serial No. 49,930

Term of patent 3½ years

(Cl. D86—10)

The bottom is plain, without design features.

I claim:

The ornamental design for a combined tray, brush and utensil holder, or similar article as shown and described.
